Claims priority, application France July 17, 1956

4 Claims. (Cl. 74—757)

In computing machines and accounting or statistical machines controlled by record cards or tapes, it is sometimes necessary for ensuring correct operation of certain parts of the machine to adjust differently the instant of operation of some parts, depending upon the required speed of operation of the machine. These differences in adjustment have the object of compensating for the effects of inertia developed during the starting or stopping of the controlled parts. It is sometimes also necessary to make some readjustments for compensating for the variations in the mechanical strength of parts which have become "harder" or "freer" after some period of operation. Particularly great difficulties arise in correctly adjusting mechanisms having a variable load, such as accumulators of accounting machines in which carry-over mechanisms may be actuated at different instants during the operation of the accumulators. The influence of the variable loads of the inertia effects and of the variations in the passive resistances may be reduced by introducing into the mechanisms permanent resistances (friction means or pawls for braking) but these resistances increase the load on the transmissions, the noise and the wear on the mechanisms. These disadvantages are obviated by providing driving devices in the single-turn clutches of the type currently employed in accounting machines. These devices ensure accurate starting and stopping of the mechanism in a clearly determined angular position independently of the load of the mechanism and of the speed of operation of the machine. For example, French Patent No. 527,463 applied for on July 2, 1920, is known, which relates to a computing machine in which the wheels of the accumulators are driven by differential mechanisms each comprising two bevel gears, one of which is coupled with a totalling wheel, and in which the starting and stopping of each totalling wheel is controlled by the actuation of an escapement mechanism which locks one of the bevel gears. In such a device, the escapement mechanism passes by an intermediate position in which the pawls of the escapement are in engagement with the two bevel gears of the differential simultaneously, which may cause deterioration of the mechanism. Moreover, in this mechanism the escapement must be maintained in its active position throughout the duration of the driving of a wheel of the accumulator.

The present invention has as its object to obviate these disadvantages and to provide a device which can be used for driving a mechanism and the stopping thereof in predetermined angular positions, while the driven mechanism can oppose within certain limits variable loads in the course of the operation and can be used at different speeds of the driving shaft of the machine.

One object of the invention is to provide a differential driving mechanism comprising a driving shaft, one or more planet wheels mechanically coupled with the said driving shaft, two bevel gears freely mounted on the said shaft and constantly in engagement with the said planet wheel or wheels, so that one bevel gear, mechani-

2

cally coupled with the mechanism to be driven, is driven by the rotation of the said shaft when the other bevel gear is locked, locking teeth on each bevel gear wheel, a control member arranged to occupy two active positions 5 for the locking of one or other of the said bevel gears, the said member comprising opposite each of the said sets of locking teeth a locking pawl, the arrangement being such that when one pawl locks one bevel gear the other pawl releases the other bevel gear, and the said 10 mechanism being characterised by the fact that there is provided an intermediate position of the control member, in which the two pawls are simultaneously disengaged from the said teeth, and in that there is provided an auxiliary locking device consisting of two locking members 15 each cooperating with the locking teeth of one bevel gear. The said locking members are rigidly connected together and so displaceable that, when a locking member is maintained out of engagement with the locking teeth of one bevel gear as a result of the rotation of the latter, the other locking member is maintained in engagement with the locking teeth of the other bevel gear and maintain it in the locked position.

The starting or stopping of a mechanism with a device designed in accordance with the invention may be 20 controlled by impulses and affords great flexibility and safety of operation, obviating any danger of deterioration of the mechanism.

Various embodiments of the invention and features thereof will be shown by way of example in the course 25 of the following description and with reference to the accompanying drawings, in which:

Figure 1 is a diagrammatic view of a driving device designed in accordance with the invention, partly in section along the line 1—1 of Figure 2,

Figure 2 is a section along the line 2—2 of Figure 1,

Figure 3 is a view of the control member actuated by an electromagnet,

Figure 4 is a view of the control member actuated by an electromagnet different from that of Figure 3,

Figures 5 to 10 are diagrammatic views of the auxiliary locking device in different positions,

Figure 11 is a diagrammatic view of a modified embodiment,

Figure 12 is a transverse section through an accumulator along the line 12—12 of Figure 14,

Figure 13 is a side view of the accumulator of Figure 12,

Figure 14 is a fragmentary plan view of the accumulator according to Figure 12 as seen in the direction of the arrows 14—14 with some of the parts removed, and

Figure 15 is an electric circuit diagram for the simplified control of a totalling wheel in addition or subtraction.

The differential driving mechanism illustrated in Figures 1 and 2 is mounted on a driving shaft 1. The planet wheels 2 and 3 of the differential can turn on a pin 4 which extends through the driving shaft 1 and the ends of which are engaged in a supporting ring 5 which supports other planet wheels 3a and 3b. The planet 55 wheels of the differential engage with the toothed rims 6 and 7 of the bevel gears 8 and 9 of the differential. The bevel gear 8 is provided with driving teeth 10 engaging with the pinion 11 of a mechanism to be driven. The said teeth are arranged to engage with a number of other mechanisms to be driven at the same time. The bevel gear 8 is provided with locking teeth 12 and the bevel gear 9 is provided with locking teeth 13. A control member 14 rockably mounted on a supporting shaft 60 65 is provided with a locking pawl 16 which is adapted to be brought into engagement with the locking teeth 12 of the bevel gear 8, and with a locking pawl 17 which

70

is adapted to be brought into engagement with the locking teeth 13 of the bevel gear 9. The bevel gear 8 meshing with the mechanism to be driven will be termed the "active bevel gear," while the bevel gear 9 locked while the bevel gear 8 drives a mechanism will be termed the "passive bevel gear." In the inoperative positions illustrated in Figure 1, the pawls 16, 17 are both disengaged from their corresponding locking teeth. A starting electromagnet 18 attracts, when energised, a plunger arm 19, which is provided with a bar 23 engaged in a fork 24 provided in the control member 14, which rocks to the left and engages the locking pawl 17 in the teeth 13 of the passive bevel gear 9. A stop electromagnet 20 attracts, when energised, a plunger arm 19 which rocks the control member 14 to the right and engages the locking pawl 16 in the locking teeth 12 of the active bevel gear 8. Two springs 21 and 22 mounted on a support 31 act on the bar 23 and normally maintain the control member in the inoperative position illustrated in Figure 1.

An auxiliary locking device comprising the member 25 mounted freely on a fixed pin 30 comprises a lever 26, which will be termed the "active lever," because it is associated with the locking teeth of the active bevel gear 8, and a lever 27, which will be termed the "passive lever," because it is associated with the passive bevel gear 9. The lever 26 is provided with a roller 28 illustrated in Figure 1, which is engaged in the locking teeth 12 of the active bevel gear 8. The lever 27 is provided with a roller 29 illustrated out of engagement with the locking teeth 17 of the passive bevel gear 9.

The driving shaft 1 turns in the direction of the arrow F and drives the planet wheels of the differential in this movement. The roller 28 being engaged in the locking teeth 12 of the active bevel gear 8, prevents the latter from turning. The planet wheels driven by the driving shaft engage on the one hand with the toothed rim 6 of the bevel gear 8, which is locked by the roller 28, and on the other hand with the toothed rim 7 of the bevel gear 9, which is driven at a speed of rotation twice the speed of rotation of the driving shaft. By the rotation of the bevel gear 9, the locking teeth 13 of this bevel gear urge the roller 29 out of engagement with the said teeth and the thrust of the teeth on the said roller, by rocking the member 25, maintains the roller 28 in engagement with the locking teeth 12 of the bevel gear 8, which is maintained locked, as also is the pinion 11 which is in engagement with the driving teeth 10 of the bevel gear 8. The various relative positions occupied by the control members in the course of the operation of the device are illustrated in the diagrammatic Figures 5 to 10. The position of the control member in Figure 5 corresponds to that of Figure 1, which is the inoperative position.

Starting of the driving mechanism

When the start electromagnet 18 (Figure 1) is energised, it causes the locking of the bevel gear 9 as already explained. The planet wheels 2, 3 which rotate continuously about the axis of the driving shaft, engage with their teeth in the toothed rim 7 of the bevel gear 9, which is held fast, and react on the teeth of the rim 6 of the bevel gear 8, which is then set in movement. The tooth 12a (Figures 1 and 6) of the teeth 12 forces the roller 28 out of engagement with the teeth 12 and rocks the member 25, which engages the roller 29 of the lever 27 (Figure 7) in the gap 13b in the teeth 13. The teeth 12 in movement, by acting on the roller 28, maintain the roller 29 engaged in the gap 13b in the locking teeth 13 of the bevel gear 9, which is thus locked. From this instant, the energisation of the electromagnet 18 may be interrupted to allow the spring 21 (Figure 1) to return the pawl 17 to the inoperative position. The resistances of the mechanism driven by the bevel gear 8 produce through the planet wheels, reactions on the passive

bevel gear 9. If, for example, the driven mechanism is locked or brakes the active bevel gear 8 to the point of reducing its speed (which was twice that of the driving shaft), the reaction of the planet wheels on the bevel gear 9 forces the roller 29 away from the teeth 13, the member 25 rocks and the bevel gear 8 is no longer driven in a determinate manner by the driving shaft. In order to compensate for the reaction of the driven load during operation on the roller 29 engaged in the locking teeth of the bevel gear 9 (Figure 8), the locking lever 26 has been made with a length L greater than the length l of the locking lever 27. Owing to the difference in the length of the levers, the roller 29 exerts on the locking teeth 13 a pressure stronger than the pressure exerted on the roller 28 by the locking teeth 12. In addition, the locking levers are so disposed that, in relation to the direction of rotation of the bevel gears, the lever 27 is in abutment with the teeth of the passive bevel gear 9. A similar condition is produced in the device illustrated in Figure 11, in which the control member 14a and the locking device 25a consist of sliding members. In this arrangement, the tooth 13c of the bevel gear 9a abuts the roller 29a while the teeth 12c force the roller 28a in the direction of the arrow E.

Stopping of the driven mechanism

To stop the bevel gear 8 and thus the driven mechanism the electromagnet 20 (Figure 1) is energised, and the pawl 16 engages the locking teeth 12 of the active bevel gear 8 (Figure 9). When the tooth 12b abuts the pawl 16 (Figure 10), a tooth gap 12d is stopped in an appropriate position to receive the roller 28, which engages in the gap 12d due to the rocking of the member 25 under the action of the teeth 13 of the bevel gear 9, which forces the roller 29 out of engagement. The pawl 16 can then be disengaged by interruption of the energisation of the stop electromagnet 20. Since the bevel gear 9 has only to supply the effort necessary to hold the roller 29 out of engagement and does not drive the mechanism, the reactions of the planet wheels on the bevel gear 8 are reduced and cannot force the roller 28 out of engagement. The device for actuating the control member illustrated in Figure 3 is equivalent to that illustrated for the control of a totalling wheel driving device in the aforesaid French Patent No. 527,463. Mention has already been made of the disadvantage of this arrangement, which requires that the start electromagnet 18a should be maintained in the energised condition throughout the time during which the mechanism coupled with the active bevel gear is to be driven. Figure 4 shows a control member 14a actuated by means of an electromagnet operating with a polarised blade. The control member is provided with a soft-iron shank or blade 32 which extends through an aperture 33 formed in a permanent magnet 34, the north and south poles of which are marked N and S respectively. The blade 32 also extends through an induction coil 35, and is maintained in the central inoperative position by a resilient device not shown. When an electric current is set up in the coil 35, the blade is attracted either by the north pole or by the south pole of the permanent magnet, depending upon the direction of the current in the coil, and thus effects the starting or stopping of the mechanism.

When the driving shaft 1 is stopped and when the device of Figure 1 is inoperative, and no locking pawl is engaged (in contrast to what is the case with the device illustrated in Figure 3), the position of the auxiliary locking device is indeterminate and the starting of the driving shaft can bring about the involuntary starting of the mechanism coupled with the active bevel gear of the differential.

In order to obviate this disadvantage, a brake is provided which consists (Figures 5 and 12) of a spring blade 36, one end of which is fixed to a fixed bar 37. The other end of the blade rubs on a portion of the mem-

ber 25 so as to maintain the said member, in the absence of any other action, in the position in which it is situated when the driving shaft is stopped. Thus, when the driving shaft of the device is re-started the latter starts again in the operative condition in which it was when the driving shaft was stopped. A similar device is illustrated in Figure 11, in which a spring 38 maintains the sliding member 25a in the position into which it has been brought. In another arrangement illustrated in Figure 6, the member 25 is provided with a shank 38 which rocks between two magnetised bars 40 and 41 and is magnetically held against one bar or the other depending upon the position into which it is brought under the action of the locking teeth of the bevel gears on the rollers of the locking levers.

Figure 12 illustrates in transverse section an accumulating mechanism for a record card accounting or statistical machine. Reference may be made by way of indication to the French patent applied for on January 8, 1936, No. 811,724, and to the first addition to the said patent, applied for on February 12, 1936 and granted under the No. 47,642, in which there is shown an example of the use of accumulating mechanisms. An accumulating unit normally comprises 12 totalling wheels, each totalling wheel being coupled with a rotary distributor switch and with a system of cam-controlled electric contacts to close and open contacts controlling the carry-over circuits. In order to deal with numbers comprising more than 12 digits, electrical connections may be established to combine a number of accumulators, and to deal with numbers comprising only a few digits the wheels of one accumulator may be used in groups of three or multiples of three wheels. In the accumulating mechanism illustrated in Figure 12, the mechanism by which the totalling wheels are driven is that illustrated in detail in Figures 1 and 2.

In the following description, identical members will be designated by the same references. The driving shaft 1 supports differential driving mechanisms comprising a bevel gear provided with teeth 10 meshing with a pinion 11 of insulating material, which is arranged to rotate freely on a pin 47. The said pinion supports the contacts 42 and 43 of a rotary switch. When the pinion is driven the said contacts travel successively over contact studs 50 to 59, which are thus successively electrically connected to a contact segment 44.

The contact studs and the contact segment of each switch are connected to output studs PX, P1, P2, . . . P9, P0 connected to the utilisation circuits of the machine (not shown). The contact studs, the contact segments and the connections to the output studs are constituted by printed circuits on insulating plates 45, 46 mounted on supporting bars 48—49, each insulating plate bearing the printed circuits of one switch on each face. The control members 14 are mounted on the supporting shaft 15 and actuated by start and stop electromagnets 18 and 20. The auxiliary locking devices comprising the members 25 are mounted on the shaft 30. There also meshes with the teeth 10 a toothed pinion 60 mounted freely on a shaft 62. Keyed on each pinion 60 is a carry-over cam 61 which, when driven, pushes at each revolution a carry-over contact lever 63. Since the operation of the carry-over circuits of accumulators is known to the person skilled in the art, it will not be described. The supporting shafts 47, 30, 15 and 62 are supported in the accumulator by side plates 72 and 73 (Figures 12 and 13). The side plates are connected by cross bars 64 and 65 and supporting bars 66, 67, 68, which support the stop electromagnets 20, the start electromagnets 18 and the insulating supports 74 of the carry-over contact blades respectively. The spring blades 36 form brakes for the members 25. The said bars also form cross members between the side plates of the accumulator. Keyed on the driving shaft 1 is a pinion 69 (Figure 13) driven through pinions 71 and 75 by the shaft 76, which drives

a number of accumulators. Keyed on the pinion 77 meshing with the pinion 69 is a cam 78 which, at each revolution, actuates the bars 79 for resetting the carry-over contacts by acting on the lever 18 through a roller 81 which is constantly applied against the cam 78 under the action of a return spring 82. For the sake of clarity, the bars 37, 48 and 64 (Figure 12) are not shown in Figure 14.

An accumulator provided with driving devices designed in accordance with the invention may be employed directly for addition and for subtraction.

Figure 15 is a very simplified diagram illustrating the principle of the electric circuits provided for this mode of use in a machine controlled by punched record cards.

15 The record cards are successively fed into the machine and pass in the direction of the arrow D under scanning brushes disposed in rows. The first row, called the upper brush set BS, scans the control perforations indicating the operation to be carried out on values which are thereafter analysed during the passage of the card below the brushes of the lower brush set BI. In the punched card 90 partly illustrated in Figure 15, record perforations are formed in horizontal rows of value 9 to 0, 11 and 12 and in vertical columns. Each column thus comprising 20 the positions for the perforations of value 9 to 0, 11 and 12 is scanned by a brush. All the perforations of like value are simultaneously scanned. The perforations for the number 2147 are indicated on the card in Figure 15.

25 A perforation S in the row of value 12 may be utilized to control the subtraction of this number from a number already introduced into an accumulator. The arrangement of the contacts illustrated in solid lines corresponds to the arrangement for the introduction of a number during addition. A manually operable contact

30 91 permits, when closed, of effecting the introduction of a number during subtraction after the scanning of a perforation S during the passage of a card under the upper brush set. The contact 91 being shown open, the introduction will be made for the purpose of addition.

35 40 The basic circuits have been illustrated only for the brush 92 of the upper brush set BS and only for the brush 93 of the lower brush set BI. The operation of the circuits for the brushes scanning the other columns of perforations indicated is similar. For the addition, the passage of a perforation 4 under the brush 93 establishes

45 the following circuit: from the positive pole of the current source, through the line 94, the contact 95 closed by the cam 95c during the passage of the record positions 9 to 0 of the card below the scanning brush set BI, through the contact brush 96, the contact roller 97

50 50 and the perforation 4, the current flows through the brush 93, the line 98, the contact 99 and the start electromagnet 18 which is energised, the line 100 and the negative pole of the current source. The energisation of the start electromagnet at the instant of the scanning

55 55 of the perforation 4 of the card starts the corresponding totalling wheel. This wheel continues to rotate synchronously with the movement of the card until the instant when the row 0 of the card travels under the analysing brush set. At this instant, the said wheel like all the

60 60 other totalling wheels started during the scanning of a card, is stopped by the closing of the cam contact 101, which establishes the following circuit: positive pole, closed cam contact 101, contact 102, line 103, contact 104, stop electromagnet 20, line 100, negative pole of the current source. The totalling wheel started by the scanning of the perforation 4 has at this instant recorded

65 70 the value 4 in the tens order of the accumulator by turning the corresponding switch through four studs. For the subtraction, the process is different. It is known that it is possible to subtract one number from a larger number by the addition of the complement to 9 of each digit to be subtracted and by effecting a carry-over for correction of the result. It is known to effect such an addition of the complement in punched-card machines by rotating the totalling wheels at the instant when the row of per-

foration positions of the value 9 of the card passes below the scanning brushes and to stop each wheel as a result of the scanning of a perforation in a corresponding column of the card. An accumulator in which the wheels are provided with the driving mechanism according to the invention lends itself with advantage to the performance of the subtraction in the aforesaid manner. An accumulator having six totalling wheels will be considered, in which the number 42595 is already situated. For subtracting the number 2147 from this number, it is necessary to add to 42595 the complement to 9 of 2147. For six totalling wheels, this complement is 997,852. The result of this addition is 1,040,447. This result is corrected by introducing into the units order the carry-over which would take up a position in a seventh totalling wheel for the millions order. The corrected result obtained is 40,448.

$$\begin{array}{r}
 42,595 \\
 +997,852 \\
 \hline
 (1) ,040,447 \\
 \hline
 1 \\
 \hline
 040,448
 \end{array}$$

In accordance with the diagram of Figure 15, the digit 4 of the tens order is introduced into the accumulator in the following manner:

A contact 91 being closed, the passage of the perforation S below the brush 92 of the upper brush set BS closes the following circuit: positive pole, lines 94, 106, contact brush 107, contact roller 108, perforation S, brush 92, closed contact 91, cam contact 105 closed at the point 12 only, electromagnet 109, line 100, negative pole. The energisation of the electromagnet 109 rocks the contact blades 105, 106, 107 and 108, which take up the position indicated in broken lines in the diagram. The electromagnet 109 is maintained energised by the contact 110 through the cam contact 111. Means not shown are provided to prevent the scanning of a control perforation in the following card from modifying the control circuits established for the preceding card. During the passage below the brush set BI of the row of perforation positions for the value 9 in the card 90, the following circuit is established: positive pole, cam contact 112 (this contact closes only at the point 9), contact 113, line 103, contact 114, start electromagnet 18, return to negative. The six wheels of the accumulator which are allocated to the subtraction start at the point 9 except those for which a perforation 9 is scanned. In this case, the simultaneous energisation of the two electromagnets 20 and 18 controlling a totalling wheel has no effect on the member controlling this wheel. The scanning of the perforation 4 in the card which is then effected by the brush 93 energises the electromagnet 20, which stops the totalling wheel of the tens order which has at this instant advanced by five units. Before the instant when the row of positions for the perforations of the value 0 in the card passes below the brushes, the cam 111 interrupts the holding of the relay 109, the contact blades 105 to 108 of which return to the position indicated in solid lines. All the stop electromagnets 20 are energised by the cam contact 101, which closes at the point 0, and the wheels which have not been stopped by the scanning of a perforation situated in a row of value between 9 and 0 are stopped.

A special connection feeds to the units order wheel (as already stated) the carry-over emanating from the highest order of the group of totalling wheels.

The wheel of the tens order of the accumulator, advanced by five units, represents the tens digit of the result and has produced the transmission of a carry-over.

The embodiment described by way of example is in no way limitative and the invention is applicable notably to selector-distributors employed in automatic telephony and to all like devices, and any modifications in the form and arrangement of the parts may be made in the mecha-

nisms depending upon the circumstances and applications without departing from the spirit of the invention.

I claim:

1. A differential driving mechanism comprising two bevel gears mounted rotatable on a common shaft, one or more planet wheels, constantly engaged with said two bevel gears, said planet wheel or wheels being driven with a continuous rotational movement about the axis of said shaft, means connecting one bevel gear with one or more mechanisms to be driven, first locking means comprising for each bevel gear at least one set of locking teeth and a locking pawl normally held out of engagement with the said locking teeth, control means for said pawl comprising an electromagnet so disposed that the temporary energisation of said electromagnet brings said pawl into engagement with the locking teeth of the corresponding bevel gear locking said bevel gear, said first locking means being adapted to lock one bevel gear or the other so that the unlocked bevel gear is rotated by the movement of the planet wheel or wheels, said control means being so arranged that the simultaneous energisation of the two electromagnets has no effect on said pawls, and second locking means adapted to maintain the locked bevel gear in its locked position under the action of the movement of the locking teeth of the driven bevel gear.

2. A differential driving mechanism comprising two bevel gears mounted rotatable on a common shaft, one or more planet wheels constantly engaged with said two bevel gears, said planet wheel or wheels being driven with a continuous rotational movement about the axis of said shaft, means connecting one bevel gear with one or more mechanisms to be driven, first locking means comprising for each bevel gear at least one set of locking teeth and a locking pawl normally held out of engagement with the said locking teeth, control means for said pawl comprising an electromagnet so disposed that the temporary energisation of said electromagnet brings said pawl into engagement with the locking teeth of the corresponding bevel gear and lock said bevel gear, the unlocked bevel gear being rotated by the movement of the planet wheel or wheels, the locking pawls of the bevel gears being rigidly fast with one another and mounted to rock about a fixed axis, a spring device normally maintaining said pawls out of engagement with the locking teeth of the bevel gears, and second locking means adapted to maintain the locked bevel gear in its locked position under the action of the movement of the locking teeth of the driven bevel gear.

3. A differential driving mechanism comprising two bevel gears mounted rotatable on a common shaft, one or more planet wheels constantly engaged with said two bevel gears, said planet wheel or wheels being driven with a continuous rotational movement about the axis of said shaft, means connecting one bevel gear with one or more mechanisms to be driven, first locking means comprising for each bevel gear at least one set of locking teeth and a locking pawl normally held out of engagement with the said locking teeth, control means for said pawl comprising an electromagnet so disposed that the temporary energisation of said electromagnet brings said pawl into engagement with the locking teeth of the corresponding bevel gear, locking said bevel gear, the unlocked bevel gear being rotated by the movement of the planet wheels, the locking pawls being rigidly fast with one another on a support sliding along an axis and disposed so that said locking pawls can not be simultaneously brought in engagement into the locking teeth of the bevel gears, a spring device normally maintains the said pawls out of engagement with the locking teeth, and second locking means adapted to maintain the locked bevel gear in its locked position under the action of the movement of the locking teeth of the driven bevel gear.

4. A differential driving mechanism comprising two bevel gears mounted rotatable on a common shaft, one

or more planet wheels, constantly engaged with the said two bevel gears, said planet wheel or wheels being driven with a continuous rotational movement about the axis of said shaft, means connecting one bevel gear with one or more mechanisms to be driven, first locking means comprising for each bevel gear at least one set of locking teeth and a locking pawl normally held out of engagement with said teeth, control means for said pawl comprising an electromagnet so disposed that the temporary energisation of said electromagnet brings said pawl into engagement with the locking teeth of the corresponding bevel gear, locking said bevel gear, the unlocked bevel gear being rotated by the movement of the planet wheel or wheels, the locking pawls being fast with a blade adapted to rock about a fixed axis and situated within an induction coil disposed between the arms of a permanent magnet so that when a current is passing through the induction coil in one direction or in the other the

5
10
15

blade is attracted towards one arm of the permanent magnet or the other and one locking pawl or the other is brought into engagement with the locking teeth of the corresponding bevel gear, thus starting or stopping the driven mechanism in accordance with the direction of the current through the induction coil, and second locking means adapted to maintain the locked bevel gear in its locked position under the action of the movement of the locking teeth of the driven bevel gear.
